(Cl. D15—8)

To all whom it may concern:

Be it known that I, Salvatore A. Arnao, a citizen of the United States, residing at Brooklyn, New York, in the county of Kings and State of New York, have invented a new, original, and ornamental Design for a Combination High Chair and Rocking Chair, of which the following is a specification, reference being had to the accompanying drawing, forming part thereof.

In the drawing:

Fig. 1 is a perspective view of a combination high chair and rocking chair, showing my new design;

Fig. 2 is a front elevational view;

Fig. 3 is a side elevational view of the same.

Fig. 4 is a bottom perspective view of the upper or rocker portion of the combination high chair and rocking chair; and

Fig. 5 is a perspective top view of the base portion of the combination high chair and rocking chair.

I claim:

The ornamental design for a combination high chair and rocking chair, as shown.

SALVATORE A. ARNAO.
